UNITED STATES PATENT OFFICE

CLARENCE JAMES BLACK, OF NORTH LITTLE ROCK, ARKANSAS

CROSSHEAD-GUIDE ANCHOR

Application filed May 12, 1928. Serial No. 277,309.

The invention relates primarily to contrivances for anchoring the ends of cross head guides to cylinder heads, and it is the principal object of the invention to provide a rather simple, yet an efficient and reliable construction and arrangement of parts for this purpose, which does not rely directly upon the use of bolts or the like, in such positions that stripping of threads or loss of nuts, might 10 cause serious damage.

With the foregoing in view, the invention resides in the novel subject matter herein-after described and claimed, description being accomplished by reference to the accompanying drawing.

Fig. 1 is a side elevation partly broken away and in section showing the invention operatively related with a cylinder head and upper and lower cross head guides.

Fig. 2 is a vertical transverse sectional view on line 2—2 of Fig. 1.

Fig. 3 is a perspective view of a cylinder head and the guide-receiving sockets carried thereby.

Fig. 4 is a perspective view showing one of the cross head guides interlocked with one of the blocks which are receivable in the sockets of the cylinder head.

Fig. 5 is a perspective view of one of the blocks separated from the cross head guide.

Fig. 6 is a sectional perspective view of one end of one of the cross head guides.

Fig. 7 is a perspective view of one of the wedges which lock the blocks within the socket 35 ets.

In the drawing above briefly described, H denotes a cylinder head, C has reference to a cross head and G denotes the usual cross head guides.

Two projections 8 are formed integrally with and project outwardly from the cylinder head H, and with these projections, certain unique features of construction are associated, for anchoring the guides G. As the 40 construction associated with each of the projections 8 is the same, only one of such constructions will be described.

The projection 8 is provided with a socket 9 formed longitudinally therein and of rectangular cross section, and is provided with

transversely aligned slots 10 which open through two of the opposed walls 11—12 of said socket. A third side 13 of the socket 9 is beveled at its outer end as shown at 14 and diverges outwardly with regard to the 55 fourth socket side 15.

16 denotes an elongated block of rectangular cross section, of a size for reception in the socket 9, one side of said block being formed with a longitudinal groove 17 in 60 which one end of the guide G is snugly received, the guide and block being locked together, for instance, by providing the former with a dove-tail head 18 at its inner end, snugly received in a similarly shaped portion 65 19 of the groove 17. The side of the block 16 opposite the groove 17, is beveled as at 20 at its outer portion, for contact with the bevel 14 of the socket side 13, and this same side of the block is provided at its inner end 70 with an abrupt shoulder 21 disposed near the inner ends of the slots 10.

A transverse wedge 22 passes through the slots 10 and abuts the shoulder 21, and when said wedge is driven tightly into place, it 75 snugly draws the block 16 into the socket 9, during which movement, the co-acting bevels 14—20 cause said block 16 to force the guide G tightly against the flat socket wall 15. Hence, as long as blocks 16 is held in 80 position, the guide G is rigidly anchored to the cylindrical head.

Any desired provision may be made for holding the wedge 22 against accidental loosening. For this purpose, I prefer to make 85 use of a bolt 23 passed through one end of said wedge and through perforated ears 24 formed integrally with the projection 8.

It will be seen from the foregoing that although the invention is rather simple and 90 inexpensive, it will be efficient and reliable, and may be quickly applied or released as occasion may demand. Moreover, it is of such nature that when any wear takes place permitting loosening of the connection between 95 cross head guide and cylindrical head, compensation for such wear may be effected by further inward driving of the wedge 22. This wedge may be formed with a plurality of openings 25, any of which may receive 100

the bolt 23, according to the extent to which it is necessary to drive said wedge.

On account of the excellent results obtainable from the details disclosed, they are preferably followed. However, within the scope of the invention as claimed, variations may be made.

I claim:—

An assemblage of the class described comprising a body having an elongated socket of rectangular cross section, said body being formed also with transversely aligned slots opening through two opposed sides of said socket, a third side of said socket being beveled and disposed in outwardly diverging relation with the fourth side thereof, a block of rectangular cross-section having a longitudinal groove in one side, said groove having a dove-tail shaped inner end, a bar having one end snugly received in said groove, the extremity of said end of the bar being of dove-tail shape for interlocking engagement with the dove-tail shaped inner end of the groove and interlocked with said block, said block and bar end being disposed in said socket with said bar end in contact with said fourth side of said socket, the side of said block opposite said groove being beveled and contacting with said beveled third side of said socket, said beveled side of said block being provided with an outwardly facing shoulder near the inner ends of said slots, and a transverse wedge in said slots abutting said shoulder to hold said block snugly in the socket.

In testimony whereof I have hereunto affixed my signature.

CLARENCE JAMES BLACK.
